US00D611987S

(12) **United States Design Patent**
Mouclier

(10) **Patent No.:** **US D611,987 S**
(45) **Date of Patent:** **** Mar. 16, 2010**

(54) **WRITING INSTRUMENT**

(75) Inventor: **Jean Mouclier**, Montmorency (FR)

(73) Assignee: **Cartier Creation Studio S.A.**, Geneva (CH)

(**) Term: **14 Years**

(21) Appl. No.: **29/332,895**

(22) Filed: **Feb. 27, 2009**

(30) **Foreign Application Priority Data**

Aug. 28, 2008 (EM) 000993589-0001

(51) **LOC (9) Cl.** **19-06**

(52) **U.S. Cl.** **D19/46**

(58) **Field of Classification Search** ..... D19/35, D19/36, 41, 42, 43, 44, 45, 46, 47, 48, 49, D19/50, 51, 54, 55, 56, 57; 24/11 F, 11 P, 24/11 R; 401/6, 52, 99, 100, 104, 105, 106, 401/107, 108, 109, 192, 195, 243, 244, 245, 401/246, 247

See application file for complete search history.
